US00D463375S

(12) **United States Design Patent** (10) Patent No.: **US D463,375 S**
Nakayama (45) Date of Patent: **** Sep. 24, 2002**

(54) **CONNECTOR FOR PRINTED CIRCUIT BOARDS**

(75) Inventor: **Eishu Nakayama**, Osaka (JP)

(73) Assignee: **J.S.T. Mfg. Co., Ltd.**, Osaka (JP)

(**) Term: **14 Years**

(21) Appl. No.: **29/150,242**

(22) Filed: **Nov. 16, 2001**

(30) **Foreign Application Priority Data**

May 17, 2001 (JP) 2001-014122

(51) LOC (7) Cl. **13-03**

(52) U.S. Cl. **D13/147**

(58) Field of Search D13/147; 439/350, 439/352, 353, 354, 358, 489, 752
